TO CIE. ANONYME CONTINENTALE POUR LA FABRICATION DES COMP-
TEURS À GAZ ET AUTRES APPAREILS, OF PARIS, FRANCE.

APPARATUS FOR DISCHARGING GAS-RETORTS.

No. 834,710.

Specification of Letters Patent.

Patented Oct. 30, 1906.

Application filed February 1, 1905. Serial No. 243,640.

To all whom it may concern:

Be it known that I, EUGENE CHERVET, a citizen of the Republic of France, residing at Villefranche-sur-Saône, Rhône, France, have 5 invented certain new and useful Improvements in Apparatus for Discharging Gas-Retorts, of which the following is a specification.

A feature of this invention is the introduction of a scoop of sheet-iron under the caked mass of coke between this and the bottom of the retort, which then enables the whole 10 of the coke to be withdrawn in a similar manner to the action of a baker's shovel for drawing the baked bread out of the oven. This operation, which is difficult when applied 15 by hand, becomes extremely practicable when it is effected mechanically.

In the machine described herein the scoop 20 is combined with certain mechanical arrangements which have been designed and found specially useful for the mechanical manipulation of coal and coke in gas-works.

These apparatus for discharging the gas-retorts will be readily understood from the following description, referring to the accompanying drawings, which show several modifications.

Figure 1 is a side view of the machine. 30 Fig. 2 shows diagrammatically to a smaller scale the same machine arranged for conducting the coke from the retorts to the outside of the retort-house. Fig. 3 shows a machine in which the scoop is arranged so as not to be tilted, as in the preceding arrangements. Fig. 4 shows a side view of the chute with variable inclination onto which the contents of the scoop are discharged. Figs. 5 and 6 show a cross-section and plan 35 of the rear end of the scoop. Fig. 7 shows a cross-section of the scoop with fixed inclination.

The scoop A, having a U-shaped cross-section which is made to correspond as nearly 40 as possible to the internal cross-section of the gas-retort, has a front beak A', of steel, which serves to detach the caked mass of coke from the bottom of the retort. When this scoop has been slid to the end of the retort under the layer of coke, it will entirely 45 contain the latter. During the backward motion the scoop carries with it the whole

of the coke, which is thus withdrawn from the retort. In order that the scoop may be thus successively advanced and withdrawn, 55 it rests upon a support or frame B and follows the motion of a chain a, passing over guide-pulleys b b and actuated by means of any suitable mechanical transmission. The chain is fixed at c to the scoop A. It is therefore sufficient to impart motion to the chain a in one direction or the other for pushing the scoop into the retort or for withdrawing it therefrom with its charge of coke. When the scoop has returned to its original position 60 with its charge of coke, it suffices to impart to it a suitable inclination, such as that shown in dotted lines, in order to cause the coke in sliding by its own weight upon the bottom of the scoop to be discharged either 65 into a conveyer C, as shown at Fig. 1 of the drawings, or into a trolley or into a wagon 70 situated at a suitable place.

As shown at Fig. 2, the scoop may be tilted so as to be inclined to the side opposite the 75 retort-furnace in order to discharge the coke out of the retort-house either into a trolley or wagon C' or C'' or into a conveyer. The scoop in that case has its end brought opposite a trap-door in the wall, which is opened 80 at the moment of emptying the retort, so that the coke can descend from the scoop. In order to enable the scoop to be suitably inclined and also to enable it to be raised to the height of the several tiers of retorts, it 85 is requisite to be able to raise it horizontally. For this purpose the support B is guided laterally between two uprights d e, and it is raised by means of chains f f', of which the chain f' passes over guide-pulleys g g' and 90 over a pulley g² in a block attached to the counterweight D, while the return-chain f' passes over g' and upon the barrel h of a raised winch, which is actuated by means of an electric motor M on the apparatus by 95 means of a belt or other transmission.

While the scoop A is being raised parallel to itself in a horizontal position, the counterweight D descends. When it meets a stop at i, which arrests its motion, the continued 100 motion of the winch will only effect a pull upon the part f'' of the chain, whereby the scoop A is tilted, together with its support, and discharges at its lower extremity the

charge of coke contained therein. The extinguishing of the coke thus withdrawn from the retort can be effected either by any suitable extinguishers placed at C in front of 5 the retort-furnace, or it may be effected in the scoop by means of a spraying-tap E, carried by the machine and supplied from an upper reservoir F, which is connected to the tap E by means of articulated pipes j, j', 10 which allow of the motion of the scoop. The tap E sprinkles the coke, first, during the backward motion of the scoop as it issues from the retort and also when the coke slides down the inclined scoop. The extinction of 15 the coke in the scoop also has the advantage of cooling the scoop after each discharging operation.

All the mechanical operations which effect the advance and the backward motion of 20 the scoop, its upward or downward motion, and its inclination are transmitted by means of endless cables or by toothed gear, with the interposition of clutches operating either with teeth or with friction or electromagnetically, which are operated by hand-levers.

The scoop may be constructed in various ways—for example, with a front beak and solid slides or with a series of bars or strips connected to the front beak and to the rear 30 end and secured together by means of distance-pieces at intervals along their length, if necessary.

Instead of discharging the scoop by causing it to assume an inclined position it may 35 also, as shown at Fig. 3, be discharged by the action of a pushing-block arranged at the end of a pitch-chain, which is mechanically actuated by a suitable mechanism—for example, as at Fig. 3, by means of a toothed pinion G, gearing with the chain H, while this passes over a drum I. It will be presently explained how the pushing-block, which terminates the chain H, and which thus forms, so to speak, the rear end of the scoop 40 A, can, according to requirements, be fixed to the scoop or be independent thereof. When the pushing-block or end of the scoop is fixed to the latter, the forward motion of the chain H in the direction of the arrow 45 pushes the scoop A into the retort, where it is charged with the layer of coke. In drawing back the chain H, which is coiled round the drum I, under the action of the driving pinion G, the pushing-block draws the scoop 50 by means of its rear end and causes it to pass out of the retort with the layer of coke. For discharging from the scoop the coke which it contains it suffices to hold it stationary on the frame to render the pushing-block 55 independent of the scoop and to cause the chain H to move forward again. The pushing-block then moves forward in the scoop A and pushes out of it the coke, which falls from the open end thereof into a chute 60 K, the inclination of which can be varied by

means of a pinion k and a toothed sector l in order that the coke may readily slide upon the chute without assuming too great a speed, so as to avoid the concussion of the coke when arriving at the bottom of the chute, which might cause dust.

The frame L, which carries the scoop, and its actuating-chain, with pushing-block, can be raised or lowered by means of a suitable actuating mechanism, such as that shown on the drawings, for the purpose of bringing the discharging-scoop A to the level of the various tiers of retorts.

Figs. 5 and 6 show in detail how the pushing-block m, which is placed within the rear end of the chute A, can be rendered independent of the chute or be attached thereto. This pushing-block m, fixed to a stem II' at the end of the chain H, is situated within the chute in front of its rear wall n, and the stem II' has a notch o, in which is engaged a lever p, that can turn upon the axis q. Below this lever p is a rod r, which is movable in the frame L, carrying the scoop. When this rod is lowered, so as not to enter the hole s, formed in the bottom of the scoop, the scoop A is free and can move in its frame. At the same time the lever p is engaged in the notch o of the stem II' of the pushing-block, and the chain H can in advancing push the scoop 95 into the interior of the retort facing it. For discharging the scoop the rod r is raised, whereby the scoop becomes fixed to its frame. At the same time the rod r in rising lifts the lever p, which assumes the dotted position p', (shown at Fig. 5,) and the pushing-block m then becomes independent of the scoop A. In pushing forward the chain H the pushing-block m is advanced in the scoop and pushes 100 in front of it the layer of coke. When a pull is exerted on the chain H after the scoop has been pushed into the retort, the pushing-block m is made to bear against the inner face of the rear end n, and thus brings back the scoop into the original position.

The inclined chute K, which has been previously described, can also be employed for the discharge of the retorts without the scoop in the ordinary manner—that is to say, by means of a drawing-tool. It only has a fixed 110 inclination which corresponds to the inclination of the retorts of the various tiers, as shown at Fig. 4. The side of the chute which faces the heads of the retorts is formed, stepped, or notched, as shown at Fig. 4, the parts thereof being arranged with an inclination from the bottom of the chute up to the upper edge, as shown at t t', Fig. 7, so that the horizontal upper edge passes below the heads of the retorts. The effect of this is that when 115 the coke is drawn by the drawing-tool it falls along the inclined surfaces t t' and arrives on the bottom of the inclined chute K in always falling through the same distance, no matter what tier the retort may be in which is being 120 125 130 135

discharged. In this way the coke is prevented from being broken into dust.

The moving of the frame L may be conveniently accomplished by the mechanism shown in Fig. 3, in which a drum T takes up or slackens cables running over guide-pulleys 1 1', thence around pulleys 2 2' on the frame L, and thence to points of attachment 3 3' at the top of the main frame which carries the drum, the drum being driven by means of sprockets 4 and 5, the latter being on the motor-shaft.

Having now particularly described and ascertained the nature of my said invention and in what manner the same is to be performed,

15 I declare that what I claim is—

1. An apparatus for discharging retorts of gas-works or the like, including in combination a scoop adapted to be introduced into a retort beneath the charge of coke, a support 20 for said scoop, a chain connected at two points to said support, a winch arranged to raise one portion of said chain, a weight arranged to raise the other portion, and a stop for limiting the movement of said weight, 25 whereby the scoop may be tilted.

2. An apparatus for discharging retorts of gas-works or the like, including in combination a scoop adapted to be introduced into a retort beneath the charge of coke, means for 30 forcing said scoop beneath the charge and then withdrawing it, and means for spraying

water over the charge in said scoop when withdrawn.

3. An apparatus for discharging retorts of gas-works or the like, including in combination a scoop adapted to be introduced into a retort beneath the charge of coke, a support 35 for said scoop, a chain, a block within the scoop and connected to the bight of said chain so as to permit it to be pulled forward or backward by the chain, said block adapted to be fixed to the scoop to effect the advance or withdrawal of the scoop by means of the chain, and to be released from said scoop to permit it to be pushed forward. 40

4. An apparatus for discharging retorts of gas-works or the like, including in combination a scoop adapted to be introduced into a retort beneath the charge of coke, means for forcing said scoop under the charge and withdrawing it, means for tilting said scoop, and a chute for receiving the coke from the scoop, said chute being adjustable in height to avoid coke having to fall too far from the scoop into the chute. 45

In witness whereof I have hereunto signed my name, this 3d day of January, 1905, in the presence of two subscribing witnesses.

EUGENE CHERVET.
